UNITED STATES PATENT OFFICE.

JOSEPH FOURESTIER SIMPSON, OF VINELAND, NEW JERSEY.

SHIPPING-PACKAGE.

1,116,746.

Specification of Letters Patent. Patented Nov. 10, 1914.

Application filed May 27, 1913. Serial No. 770,126.

To all whom it may concern:

Be it known that I, JOSEPH FOURESTIER SIMPSON, a citizen of the United States, and a resident of Vineland, in the county of 5 Cumberland and State of New Jersey, have invented certain new and useful Improvements in Shipping-Packages, of which the following is a specification.

My invention relates to improvements in 10 packages and more particularly to improvements in packages for shipping eggs, fruit and similar articles that are of a fragile nature and liable to be broken or bruised in ordinary shipping packages, and the object 15 of my invention is to furnish a package for this purpose which will be inexpensive and efficient and all the parts of which may be separated and laid out flat for the purpose of taking up a minimum space for storage or 20 in shipment to the point where they are to be assembled for use.

My invention is illustrated in the accompanying drawings which form part of this specification and in which:—

25 Figure 1, is a plan of part of one of the halves of my shipping package; Fig. 2, a longitudinal section through two superposed halves of my package, the section being taken on line α — α Fig. 1; Fig. 3, a 30 perspective view of the longitudinal walls of my package; Fig. 4, a perspective view of the transverse dividing pieces or braces of the package; Fig. 5, a plan of blank from which the inclosing boxes are made; Fig. 35 6, a perspective view of part of slip case for securing the two parts of the package together.

Each of the two halves of my package 40 consists essentially of two elements, viz: longitudinal partitions 2 and transverse partitions 3 which may, or may not, be inclosed by the ends, sides, and bottom of a box 1 which, if used, might be made of a rectangular sheet of straw-board, or other suitable 45 material, the ends of which are slotted or slit, as at 4, Fig. 5, and which is grooved or scored as shown at 5 to facilitate its bending into box form. That part of the ends of the blank between the slits 4 is adapted, 50 when these ends are bent up and over, to form inclined ends 6, as shown in Fig. 2, which form sides for the outer ends of the pockets at the ends of the package.

The longitudinal partitions 2 are formed, 55 preferably, from a single sheet 7 of straw-

board which is scored longitudinally so that it may be bent to a zig-zag form as shown best in Fig. 3. At their tops the inclined walls of the partitions 2 are angularly cut, as at 9, for the passage of the transverse 60 partitions 3 and are perforated, if desired, at 10, to form openings through which the sides of the article carried by the pockets can pass.

The transverse partitions 3 are of less 65 depth than the longitudinal partitions 2, they are V-shaped and carried by the angular cuts 9 in the longitudinal partitions their apices being in line with the tops or apices of the longitudinal partitions. 70

The lower edges of the partitions 3 are furnished with notches or projections 11, Fig. 4, which, when they are passed through the cuts 9 in partitions 2, interlock with the lower ends of the latter and prevent them 75 from collapsing with any ordinary weight or usage.

The ends of the transverse partitions rest against the inner sides of the outer downwardly bent sides 7 of the sheet of material 80 which forms the longitudinal partitions. If the partitions be inclosed in a box 1 the sides of the sheet 7 would rest against the sides of the box while their ends would rest against its ends, however, as I have before 85 stated, the inclosing box is not necessary for the formation of a satisfactory and merchantable package although it presents a neater appearance when the box is used. 90

It will be seen that when the longitudinal and transverse partitions are assembled they 95 form a number of pockets each of a pyramidal form, that is to say the sides of the pockets slope inwardly and downwardly. For purposes of construction the sides of 95 the cross partitions 3 are narrower than those of the longitudinal partitions. There is, therefore, an open space left upon two opposite sides of each pocket, and an object carried by the sides of one pocket cannot 100 ordinarily come into contact with the sides of any other pocket nor can the sides of one pocket come into contact with the sides of another unless the package be completely crushed. 105

The package is primarily intended for carrying eggs each one of which is held, when the two parts of the package are superposed, by eight sides of two pockets in such a manner that it cannot touch either the top or bottom 110

of the pockets. This is essential for safe carriage of eggs for if they come in contact with the top or bottom of the pockets the slightest blow upon the side of the package at that point will result in a broken egg but if the eggs be suspended in the pyramidal pockets and be held thereby away from the sides of the package the latter may be subjected to very rough usage without any damage being done them. In my construction the pockets adapt themselves to eggs of varying sizes and forms being sufficiently flexible to hold all sizes of eggs so that they cannot rattle about in them. The two parts of the package being superposed, as shown in Fig. 2, may be slipped into the rectangular inclosing case 12, Fig. 6, which will hold them securely in place.

Having thus described my invention I claim as new and desire to secure by Letters Patent:

1. A shipping package comprising, in combination, a continuous sheet of material bent zig-zag to form a series of V shaped parallel channels, and a series of separate partitions, each having a V shape, adapted to pass through at right angles to the walls of said V shaped channels in such a manner that the upper edges of said channels and partitions will be substantially in the same plane, said channels and partitions forming together a series of single walled pyramidal pockets.

2. In a shipping package, in combination, a continuous sheet of material the ends of which are bent vertically and which is between the ends bent in a zig-zag to form a series of V shaped channels, and a series of V shaped transverse partitions passing through the sides of said channels, the ends of said transverse partitions engaging the

inner sides of the vertically bent ends of the continuous sheet.

3. In a shipping package, in combination, a continuous sheet of material the ends of which are bent vertically and which is between said ends bent in a zig-zag to form a series of V shaped channels, and transverse V shaped partitions passing through said channels, the ends of said transverse partitions engaging the inner sides of the vertically bent ends of the continuous sheet, said transverse partitions being notched on their inner sides to engage and prevent the sides of said channels from spreading.

4. In a shipping package, in combination, a continuous sheet of material the ends of which are bent vertically and which is between said ends bent in a zig-zag to form a series of V shaped channels, and transverse partitions having a V shape passing through the sides of said channels and abutting against the vertically bent ends of the material forming said channels, said channels and partitions mutually interlocking to prevent spreading.

5. In a shipping package, in combination, an inclosing box or frame, a continuous sheet of material having vertically bent ends and between said ends being bent in a zig-zag to form a series of V shaped channels, and a series of V shaped transverse partitions passing through the side of said channels and abutting the vertically bent ends of the material forming said channels, said channels and partitions mutually interlocking and forming one with the other a multiplicity of pyramidal pockets.

JOSEPH FOURESTIER SIMPSON.
